UNITED STATES PATENT OFFICE.

JOSEPH H. OBERMAN, JR., OF GRANVILLE, IOWA.

PUMP.

Application filed December 11, 1922. Serial No. 606,108.

To all whom it may concern:

Be it known that I, JOSEPH H. OBERMAN, Jr., a citizen of the United States, residing at Granville, in the county of Sioux 5 and State of Iowa, have invented certain new and useful Improvements in Pumps, of which the following is a specification.

This invention relates to pumps for drawing water from a well, and has for its primary object the provision of a novel construction whereby the working parts may be easily removed from the well when repairs or renewals are necessary and repairs or renewals may be made without requiring the workmen to enter the well. The invention also has for its object the provision of a novel construction and arrangement of parts whereby rigidity in the structure of the pump will be attained and the pump 10 may be operated easily to deliver a steady stream of water at the point of use. Incidental objects of the invention will appear in the course of the following description, and the invention resides in certain novel features which are illustrated in the accompanying drawings and will be hereinafter fully described and specifically set forth.

In the drawings:

Figure 1 is an elevation of a pump embodying my improvements in position in a well;

Fig. 2 is a plan view of the pump with a part in section;

Fig. 3 is a horizontal section on the line 3-3 of Fig. 1;

Fig. 4 is a vertical section on the line 4-4 of Fig. 2;

Fig. 5 is a vertical section on the line 5-5 of Fig. 2;

Fig. 6 is a plan view of the base;

Fig. 7 is an enlarged elevation of one of the guides and the working parts which passes through the same;

Fig. 8 is a horizontal section on the line 8-8 of Fig. 4;

Fig. 9 is a bottom plan view of the bridge piece as seen in the plane indicated by the line 9-9 of Fig. 4;

Fig. 10 is a detail section on the line 10-10 of Fig. 8;

Fig. 11 is a detail section on the line 11-11 of Fig. 8;

Fig. 12 is a vertical section through the

fulerum block or head which guides and supports the upper portion of the plunger rod and the handle by which said rod may be manually operated;

Fig. 13 is a rear elevation of said head;

Fig. 14 is an elevation of the delivery spout and the parts associated therewith for adjusting the main controlling valve, and

Fig. 15 is a detail perspective view of one of the packing cups.

In the drawings, the reference numeral 1 indicates a well which may be lined with brick or in any other manner, as may be preferred, and 2 indicates the curb or platform which extends across the well and supports the pump. The curb or platform is, of course, constructed with an opening to permit the pump to partly pass into the well, and extending over this opening is a base 3 which may be bolted or otherwise rigidly secured to the platform, as will be readily understood. The base 3 may have any convenient outline, and upon its upper side is provided with a column 4, a collar 5 and a plurality of guiding and supporting sleeves 6, 7 and 8, these several parts being preferably cast integral with the base. Ex-

tending through the column 4 is a sustaining tube or standard 9 which is secured rigidly within said column by bolts 10 inserted diametrically through the standard and the column, as will be readily understood. I also secure rigidly to the standard or sustaining tube a bearing sleeve 11 which may be constructed in semi-cylindrical mating members fitted about the sustaining tube and rigidly secured thereto by diametrically disposed bolts 12, as is obvious. This bearing sleeve has its lower end preferably resting upon the column 4 and may be also utilized as a support for a pump jack. Most pump jacks are standardized and have a diameter much larger than the standard 9, and I, therefore, provide the sleeve 11 which will provide a good fit for the jack. The lower end of the tube or standard 9 is secured rigidly in a bridge piece 13 which is disposed within the well, and it will be readily noted that the sustaining column or standard is disposed adjacent one end of the base 3 and also adjacent one end of the bridge piece. The lower end of the sustaining tube or standard may be secured in the

55

60

65

70

100

105

bridge piece in any desired manner but will preferably be threaded into a socket 14 formed in the bridge piece so that, if repair or renewal of these parts should be necessary, the sustaining tube may be easily withdrawn from the bridge piece. At the opposite ends of the base and the bridge piece, I provide a stiffening rod 15 which has its lower end threaded into a lug 16 on the bridge piece, while the upper end of said stiffening rod is fitted through a smooth-bore opening 17 provided therefor in the base and is equipped with nuts 18 above and below the base and adapted to be turned home against the same whereby the rod will be firmly secured in place and the base and the bridge piece rigidly connected. To fit the rod 15 in place, the lower nut 18 is adjusted to a point well below the upper end of the rod which is then inserted upwardly through the opening 17. The lower end of the rod is then screwed into the lug 16, after which the nuts 18 are brought to bear against the base. A tube 19 is inserted through the collar 5 and has its lower end threaded into the upper side of the bridge piece 13, as shown at 20, the upper end of this tube 19 being closed air-tight by a cap 21. The collar 5 is appreciably greater in diameter than the tube 19 so that, if it should be necessary to remove the tube 19, it will not bind and may be easily started, and a bushing 22 is fitted in the collar around the tube so as to close the space between the collar and the tube, and this bushing is constructed with a slot 23 to permit the end of a set screw 24 to pass into binding engagement with the tube, the said set screw being threaded through the side of the collar, as shown most clearly in Fig. 5. By turning the set screw home, the tube will be forced against the opposite side of the bushing 22 and the bushing will be clamped between the tube and the collar so that a firm support for the tube will be provided. A brace bar 25 extends between the tube 19 and the standard or sustaining tube 9, one end of the said brace bar being bolted or otherwise rigidly secured to the said standard and the opposite end thereof being formed to fit partly around the tube 19 and mate with a half collar 26 which is fitted to the said tube and is secured to the end of the brace bar by bolts 27, as will be readily understood. I thus attain a very rigid structure so that, in operation, the pump will be practically free of vibration and the several connections between the parts of the pump will remain tight. The lower end of the tube 19 is open, as shown in Fig. 5, and communicates with a passage 28 in the bridge piece so that this tube constitutes an air column to equalize the pressure upon the water, as will presently more particularly appear.

On the upper end of the standard or sustaining tube 9, I secure a cap 29 which is provided on its upper side with flanges or lugs 30 to which the head or bracket 31 is secured. The said head or bracket consists of side members provided at their lower ends on their inner faces with recesses 32 corresponding in dimensions and form to the lugs 30 so that, when the bracket or head is in the position shown in Fig. 1 and the bolts 33 are in place, the bracket will be firmly supported in proper position to guide the plunger rod. Upon its outer side, one of the side members is provided with a ledge or shoulder 34 against which the heads 35 of the bolts 33 may bear so that the bolts will be prevented from turning while the nuts 36 are driven home, the necessity of employing an extra wrench or other tool to prevent turning of the bolt being thus overcome. The side plates or members of this bracket or head are connected at their upper ends by a cap plate or bar 37 which is secured to and between the side plates by bolts 38 inserted therethrough, and it will be readily noted upon reference to Fig. 1 that the upper extremities of the said side plates are disposed out of vertical alinement with the sustaining rod 9 whereby the plunger rod may be slidably fitted through the said guide plate 37. At their lower ends, the side plates are further connected by a guide bar or plate 39 which is secured in place by bolts 40, and both guide plates 37 and 39 are provided centrally with angular openings 41 through which the flat bar 42, which constitutes the upper extremity of the plunger, is slidably fitted. One side plate is further provided with a ledge or shoulder 43 on its outer side against which the heads of the bolts 40 may bear so that these bolts will be prevented from turning while the securing nuts are driven home, and a similar ledge or shoulder 44 is provided adjacent the upper end of the side plate to prevent turning of the bolts 38. A fulcrum post 45 is mounted upon the cap 29 between the flanges or lugs 30 and projects upwardly and outwardly therefrom, as clearly shown in Fig. 1, the lower end of the post being pivotally held by the outer bolt 33. A hand lever 46 is fulcrumed upon the upper end of this post 45 and has its inner end pivotally attached to the bar 42 so that by oscillating the hand lever, the plunger will be reciprocated and the pump operated.

The lower end of the bar 42 is secured within a yoke 47 which is firmly secured upon the upper end of the plunger rod 48 and relative movement of the bar 42 and the yoke is prevented by ribs or flanges 49 on the inner surface of the yoke engaging the edges of the bar (see Fig. 4). The plunger rod 48 extends downwardly through the upper cylinder 50 and into the lower cylin-

der 51. It is to be understood that the lower cylinder 51 may be disposed at any depth, to be determined by the depth of the well, and in the present illustration it is shown as 5 threaded into a flange 52 on the under side of the bridge piece 13. If, however, the well is very deep, the cylinder will be connected with this flange by an intermediate pipe or tubing, the length of which will, of course, be determined by the depth of the well. From the lower end of the lower cylinder 51 extends a suction pipe 53 equipped at its lower end with a strainer 54 which may be of any well-known construction. The plunger rod 48 is preferably constructed in two sections connected by a coupling sleeve 55 so that the parts may be readily assembled and disassembled as occasion may require, and upon the upper end 10 of the lower section is carried the upper plunger 56. The lower plunger 57, which may be of any desired construction, is fitted to operate within the lower cylinder 51 and is secured on the lower end of the lower section 58 of the plunger rod, a coupling 59 connecting the lower plunger rod with the upper plunger rod, as shown in Fig. 4. This coupling block 59 has an angular opening or slot 60 formed diametrically through the same and above the said slot an opening 61 is formed diametrically through the block, the purposes of which will presently appear. The upper cylinder 50 has its upper end threaded into the lower end of a cylindrical coupling block or head 62 which has a reduced upper end 63 provided with flat faces, as shown at 64. A nipple 501 is threaded into the upper end of the block 62 and upon the upper end of the nipple is secured a cap 65 which encircles the plunger rod 48 and serves as a guide for the same. The coupling block or head 62 fits closely but rotatably within the sleeve 6, and this sleeve is constructed with a helical slot or opening 66 in which a pin or stud 67 upon the head 62 may play, a roller 68 being preferably mounted upon the said stud to reduce the frictional wear. The helical slot or opening 66 in the sleeve 6 extends nearly around the complete circumference of the sleeve, and at its upper end it opens into a longitudinally disposed notch 69 which will permit vertical movement of the stud 67 and the roller 68 so that, when the parts are properly positioned, the plunger rod, the coupling head, nipple, and cylinder may be lifted vertically and drawn through and from the sleeve 6. Tangential openings 70 are formed through the wall of the sleeve 6, and similar openings 71 are formed through the wall of the coupling head 62. When the openings 71 register with the openings 70, cotter pins or keys 72 are inserted therethrough so that relative movement of the head and the sleeve 15 will be prevented. By referring more particularly to Fig. 4, it will be noted that the wall of the coupling block 62 is internally thickened, as at 620, where the locking pins or keys 72 are inserted so that there will be no opening across the bore of the block and 70 a positive uninterrupted guide for the keys or pins will be provided. The sleeve 6 is constructed upon its outer side at two or more points with bridge pieces 73 so as to reinforce the sleeve and prevent collapse of 75 the same from the formation of the helical passage or slot 62 therein, and in the upper edge of the sleeve are provided diametrically opposite notches 74. When the cylinder 50 and the plunger rod have been raised to such a height that the coupling block 59 is above the sleeve 6, the flat bar 42, which has been previously disconnected from the plunger rod, is inserted through the slot 60 and engaged in the notches 74 so that the lower 80 plunger rod will be supported in such position that the upper plunger may be easily removed therefrom and, if no repairs are needed to the lower plunger, it will be supported while repairs are being made to the 85 upper plunger or the upper cylinder. The opening 61 is to be engaged by any convenient tool or device so that the plunger may be held up while the bar 42 is being withdrawn from the slot 60, or may be raised 90 after the plunger rod is removed.

The lower end of the upper cylinder 50 is disposed within a packing cup 75 secured upon the upper side of the bridge piece 13, a suitable gasket 76 being interposed between the upper surface of the bridge piece and the under surface of the packing cup, as will be readily understood. The packing cup is provided internally with an annular shoulder 77 against which the edge of the 95 packing ring or diaphragm 78 may engage, the said packing ring or diaphragm resting upon the upper end of a spider 79 which is threaded onto the lower end of a shoulder or collar 80 which is threaded onto the cylinder 100 with the packing ring disposed between the spider and the shoulder and clamped thereby. It will be readily understood that, when the parts are associated in proper relation, the packing will be forced against the internal surface of the packing cup and the pressure of the water which may reach the packing ring will simply force it outwardly 105 more closely against the packing cup and thereby aid in making the joint leak-proof. The plunger 56 works closely within a lining 81 in the cylinder 50, and this lining is preferably of brass so that it will not corrode under the action of the water. The lower 110 end of the lining is flared, as indicated at 82, so that the plunger may readily enter the same in the event that it should happen to make a stroke carrying it below the lining, while the upper end of the lining is constructed with claws or spurs 83 fitting in 115

120

125

130

- 4
- openings 84 in the cylinder. The said claws or teeth 83 prevent downward movement of the lining, while the flared formation on its lower end will prevent upward movement thereof. The shoulder 80 is provided externally with longitudinal grooves or notches 85 so that it may be readily engaged by a turning tool when the parts are to be separated.
- 10 If repairs to the plunger or the cylinder should be necessary, the flat bar 42 which constitutes the upper extremity of the plunger rod is disconnected and removed from the guide bars or plates 39 and 37.
- 15 The inner bolt 33 is then removed and the bracket or head 31 may then be swung rearwardly about the outer bolt 33 as a pivot. The keys or cotter pins 72 are then withdrawn and a wrench or other tool is fitted to the reduced end 63 of the coupling head 62 and said head is rotated so that the stud 67 will be brought to the lower end of the vertical notch 69, after which the cap 65 and the nipple 501 are firmly grasped and lifted. It will be readily noted that the diameter of the head 62 and the internal diameter of the sleeve 6 is somewhat greater than the external diameter of the packing 78 so that, when the cylinder is lifted, it may be drawn through the sleeve 6 until the lower end of the plunger rod or the coupling 59 is above the upper end of the said sleeve, whereupon the coupling may be supported, as previously described. The plunger rod is then disconnected from the said coupling and the plunger and the cylinder may be repaired at once or laid aside to be repaired as circumstances require or permit. Inasmuch as the coupling head 62 is firmly secured to the cylinder 50, the rotation of the head will, of course, rotate the cylinder and, therefore, the parts mounted on the lower end of the cylinder will rise with it as the stud 67 or the roller 68 travels upwardly along the helical slot 66. The plunger rod may possibly tend to move downwardly through the cylinder as this upward movement is imparted to the cylinder, but such downward movement of the plunger will be arrested by contact of the yoke 47 with the cap 65 so that the plunger will be withdrawn from the well with the cylinder.
- 20 The bridge piece 13 is, of course, constructed with an opening or port, indicated at 86, which is alined with the lower cylinder 51 and constitutes the inlet port for the water, and this inlet port is, of course, in vertical alinement with the bore of the packing cup 75 and extends vertically through the bridge piece. A passage 87 extends through the bridge piece laterally from the port 86 to the end of the bridge piece more remote from the socket 14 and one outlet for the water is arranged in the top of the bridge piece over the end of the said passage 87. A packing cup 88, corresponding in all respects to the packing cup 75, is secured upon the bridge piece over the said end of the passage 87 and a delivery tube 89 has its lower end disposed within the said packing cup. This delivery tube is constructed of two axially alined sections threaded into the upper and lower ends, respectively, of a coupling head 90 corresponding to the coupling head 62 and fitting within the sleeve 8 in the same manner that the said head 62 fits within the sleeve 6. The sleeve 8 is constructed with a helical slot 91 and the head 90 is equipped with a stud 92 playing in the said slot in the same manner that the stud 67 plays in the slot 66. Cotter pins 93 secure the head 90 against movement within the sleeve 8 just as the cotter pins 72 secure the head 62 against movement, it being noted that the coupling 90 is provided with an internal enlargement 900, corresponding to the enlargement 620, and is further provided with a recess 901 at a point diametrically opposite the enlargement so that the cross-sectional area of the bore will not be reduced to restrict the flow of the water. The provision of the enlargement 900 also prevents leakage around the locking pins or keys. Upon the lower end of the delivery tube 89 is fitted a packing ring or diaphragm 94 which may engage an internal shoulder 95 on the packing cup 88, and this packing ring is clamped to a shoulder 96 upon the tube 89 by a cage or sleeve 97 which is threaded onto the lower end of the tube 89 and is provided internally with a spider 98 constituting a guide for the valve stem 99. The lower end of the sleeve 97 is preferably beveled or flared, as shown at 100, so that it will constitute a seat for the valve 101 which may conveniently be a rubber ball secured upon the stem 99 by nuts 102 disposed above and below the ball, as clearly shown. Upon reference to Fig. 4, it will be noted that the valve 101 may engage the seat 100 or may engage the seat 103 which is below the valve. The position of the valve is determined by vertically adjusting the stem 99 so that the water may be directed into and through the delivery tube 89 or may be directed to and into the underground service pipe to be presently described. Upon the upper end of the delivery tube 89, I secure a spout 104 through which the water may be discharged. The stem 99 extends through the top portion of the spout and said top portion is constructed to receive a packing nut 105 adapted to be turned home against packing 106 so that the said packing will be compressed about the stem 99 and leakage of the water prevented. The

stem extends through the nut 105 and above the same is enlarged and threaded, as shown at 107, the extreme upper end of the stem being angular in cross section, 5 as shown at 108. If preferred, the enlarged threaded part 107 may be separate from and threaded onto the stem 99. A sustaining and guiding head 109 is secured upon the spout and projects upwardly therefrom and is provided with the lugs or branches 110 through which the threaded and angular portion of the valve stem passes. Between the lugs 110, a hand wheel 111 is mounted and this hand wheel 10 15 is constructed with an internally threaded hub engaging the threaded portion 107 of the valve stem so that rotation of the hand wheel will effect vertical movement of the stem and consequently adjust the valve 101, 20 as desired.

The chamber 28 in the bridge piece 13 is a lateral branch or extension of the passage 87, as shown most clearly in Fig. 8. In the under side of the bridge piece 25 is a groove 112 which forms the upper portion of a passage connecting the port of the valve seat 103 with a port 113 which, in turn, establishes communication with the outlet chamber 114. A flange 115 is 30 secured to the under side of the bridge piece and this flange is provided in its upper side with a groove or recess 116 mating with the groove 112 so as to provide a passage to convey water to the underground service connection. Extending 35 through the side wall of the chamber 114 is a threaded port 117 into which the end of the underground service pipe 118 is fitted. A check valve 119 is adapted to 40 rest upon the valve seat 113, and this valve obviously will permit the flow of water to the outlet 118 but prevent flow in the opposite direction. The check valve is preferably a rubber ball secured upon a 45 stem 120 by nuts 121, and the said stem extends up to and through a spider 122 formed within a sleeve or cage 123, the said sleeve or cage being threaded onto the lower end of a tube 124 which is disposed 50 within a packing cup 125 provided on the upper side of the bridge piece. The sleeve or cage 123 is slightly tapered downwardly to reduce friction and clamps a packing ring or diaphragm 126 against a 55 shoulder 127 threaded upon the tube 124, which packing ring cooperates with the packing cup 125 in the same manner that the packing ring 78 co-operates with the packing cup 75 and the packing ring 94 co-operates with the cup 88. Upon the upper end of the stem 120 is a nut 128 which is adapted to rest upon the spider 122 and thereby limit the downward movement of the check valve. If a new check valve is 60 65 needed, the tube 124 is withdrawn from the

packing cup 125 and, of course, the check valve and the other attached parts will be simultaneously withdrawn. The sleeve or cage 123 obviously may be then removed from the tube 124 and the nut 128 will 70 then be accessible so that by withdrawing the same from the stem 120 the parts may be separated. Of course, by reversing these steps, the parts may be re-assembled in operative relation. The tube 124 is threaded at its upper end into a head 130 fitting within the sleeve 7 in the same manner that the head 62 fits within the sleeve 6 and the head 90 fits within the sleeve 8. The sleeve 7 is of the same construction as 80 the sleeves 6 and 8, and the head 130 is secured therein by pins or keys 131 in the same manner that the heads 62 and 90 are secured, corresponding in all respects to the head 90. A nipple 140 is threaded into 85 the upper end of the head 130 and a cap 129 closes the upper end of the nipple. When repairs to the tube 124 or the check valve are needed, the cotter pins or keys 131 are withdrawn and the head 130 is then 90 rotated so that an upward movement will be imparted to the tube and the parts associated therewith. The tube 124 constitutes an air chamber to equalize the pressure on the water, and it will be readily 95 noted that I have provided two air chambers, one in advance of the check valve and one behind the said valve so that, when the water is being delivered into the underground service pipe 118, a very even 100 flow of the liquid will be attained.

The packing cups upon the bridge piece 13 are substantially duplicates in construction and are secured upon the bridge piece by bolts inserted through the flanges 132, at 105 the lower ends of the cups, into the bridge piece. It will, of course, be understood that the securing bolts are inserted through the bridge piece and some of them are also utilized to secure the flange 115 to the under side of the bridge piece, the nuts being fitted on the lower ends of the bolts. As one of these bolts will be located at a point between the cups 75 and 125 and will be rather inaccessible, I provide a lug or offset 110 133 on the cup 125 against which the head of the bolt will bear so that rotation of the bolt will be prevented while the nut is being driven home.

It will be readily noted from the foregoing description, taken in connection with the accompanying drawings, that I have provided a construction which will permit the working parts to be easily withdrawn 115 from the supporting structure without requiring a workman to enter the well and operate at the bottom of the same. This advantage of my pump is attained without any sacrifice of efficiency and the pump will 120 operate easily to deliver water at the mouth 125 130

of the well or through an underground service to a distant point. When the water is to be delivered at the mouth of the well, the hand wheel 111 is turned so that the 5 valve stem 99 will be driven downwardly and the valve 101 caused to engage the seat 103. The flow of water through the passage provided by the grooves 112 and 116 to the underground service connection will be 10 thereby prevented and the water will rise through the delivery tube 89 to the spout 104. If the valve be caused to engage the seat 100, the flow of water through the delivery tube 89 will be prevented and it will 15 flow to and through the underground service pipe, as will be readily understood. The packing cups and the guiding and supporting sleeves are obviously peculiarly adapted to permit the withdrawal of the working 20 parts from the well so as to facilitate repairs or renewals. At the same time the guiding and supporting sleeves upon the base 3 serve to impart rigidity to the pump structure so that the loosening effect of vibration 25 during the operation of the pump is neutralized and practically eliminated while the provision of the packing cups and the described manner of packing around the lower ends of 30 the working parts facilitates the assembling of the working parts and also prevents leakage of water at the joints. It will be readily noted that the air chamber provided by the tube 19 is in direct communication with the water inlet passage so that the pressure 35 of the air trapped in this air chamber will assist in raising the water through the delivery tube 89, as well as serve to maintain a steady even flow thereof at the spout. When the water is being delivered into the 40 underground service pipe, the hammering of the check valve will be overcome inasmuch as there will be operative air chambers at the opposite sides of the said valve serving to equalize the pressure upon the water and 45 tending to maintain a steady even flow thereof.

Each of the packing cups has an internal annular shoulder and the edge of the packing ring may engage with said shoulder but 50 such engagement is not necessary, the essential function of the shoulder being to serve as a stop. Should it be necessary to provide a new tube 124, for instance, and the new tube be cut too long, the internal shoulder 55 of the cup 125 would arrest the descent of the tube before the openings in the head 130 registered with the openings in the sleeve 7 so that the operator would at once see that the new tube was too long and how much 60 should be cut off. It will be noted that the inner walls of the packing cups are vertically cylindrical but slightly flared at their upper ends to facilitate the insertion of the packing rings. The edges of the rings are 65 turned downward and the packing contact

is effected between the outer surface of the packing ring and the inner surface of the cup.

Having thus described the invention, what is claimed as new is:

1. In a pump, the combination of a supporting structure having a guide thereon, a working element extending through said guide, and means connected with the working element and co-operating with said guide 75 to effect lifting of said element whereby it may be withdrawn from the supporting structure.

2. In a pump, the combination of a supporting member having an upright guide 80 thereon, said guide having an obliquely disposed portion, a member passing through said guide, a working element associated with said member, a head on said member, and means on the head to engage the obliquely disposed portion whereby to effect withdrawal of the member passing through the guide and the working element associated with said member.

3. In a pump, the combination of a base, 90 a vertical sleeve on the base provided with a helical slot and a vertically disposed notch at the upper end of said slot, a member passing through said sleeve, a working element associated with said member, and a projection 95 on said member engaging in the said slot whereby rotation of the member will effect withdrawal of the same and the working element associated therewith.

4. In a pump, the combination of a base, 100 a vertically disposed sleeve on the base, a bridge piece below the base and having passages therein for the flow of water, a packing cup secured upon the bridge piece in vertical alinement with the sleeve on the 105 base, a member passing through the sleeve and having its lower end disposed within the packing cup, packing on the lower end of said member engaging the inner wall of the cup, a working element associated with 110 said member, and means on the member engaging the sleeve whereby rotation of the member will effect withdrawal from the base and the bridge piece of the said member and the working element associated therewith. 115

5. In a pump, the combination of a base, a sleeve thereon having a helical slot and provided with notches in its upper edge, a cylinder passing through the said sleeve, means on the cylinder to engage the helical slot in 120 the sleeve whereby rotation of the cylinder will effect an upward movement thereof, a plunger rod working in the cylinder, a lower plunger rod, a coupling connecting the two plunger rods, said coupling having a 125 diametrical opening therethrough, and a bar detachably secured to the upper end of the upper plunger rod, said bar being adapted to pass through the opening in the coupling and rest in the notches in said sleeve where- 130

by to support the lower plunger in a raised position.

6. In a pump, the combination of a base, a sleeve thereon, a member passing through the said sleeve, a working element associated with said member, a head on said member fitting closely within the sleeve, said head and said sleeve being provided with registering tangential openings, and fastening devices adapted to be inserted through said openings whereby to prevent movement of the head within the sleeve.

7. In a pump, the combination of a base, a bridge piece disposed below the base and connected therewith, the said bridge piece being provided with an inlet port in its bottom and having an outlet port in its top and a second outlet port in one side, a passage connecting the inlet port with the first-mentioned outlet port, a second passage connecting the first-mentioned passage with the second outlet port, and a valve arranged to seat in the first outlet port or in the second passage immediately below said outlet port.

8. In a pump, the combination of a base, a bridge piece disposed below the base and rigidly connected therewith, said bridge piece having an inlet port in its bottom, an outlet port in its top and a second outlet port in its side and provided with a passage leading from the inlet port to the first-mentioned outlet port and a second passage leading from the first-mentioned passage to the second outlet port, a valve controlling the

said passages, means for setting said valve whereby the flow will be directed through either outlet port, a check valve at the second outlet port, and air chambers at opposite sides of said check valve.

9. In a pump, the combination of a frame member, an upwardly flared packing cup secured upon said member and provided with an internal annular shoulder, a tubular member having its lower end disposed within said cup, a working element associated with said member, a packing ring fitted about the lower end of said member and having its edge turned downwardly to engage the annular shoulder on the packing cup, and clamping members mounted upon the tubular member at opposite sides of the packing ring and securing the same.

10. In a pump, the combination of a base, a sleeve thereon provided with notches in its upper edge, a cylinder passing through and removable from the sleeve, a plunger rod working in the cylinder, a lower plunger rod, a coupling connecting the two plunger rods, said coupling having a diametrical opening therethrough, and a bar detachably secured to the upper end of the upper plunger rod, said bar being adapted to pass through the opening in the coupling and rest in the notches in said sleeve whereby to support the lower plunger in a raised position.

In testimony whereof I affix my signature.
JOSEPH H. OBERMAN, JR. [L. s.]
